Attorney.

UNITED STATES PATENT OFFICE.

GEORGE WILLIAM MASCORD, OF LONDON, ENGLAND.

APPARATUS FOR FEEDING WEB REELS OR ROLLS IN ROTARY NEWSPAPER PRINTING AND SIMILAR MACHINES.

1,410,825.

Specification of Letters Patent. Patented Mar. 28, 1922.

Application filed October 19, 1920. Serial No. 418,079.

(GRANTED UNDER THE PROVISIONS OF THE ACT OF MARCH 3, 1921, 41 STAT. L., 1313.)

To all whom it may concern:

Be it known that I, GEORGE WILLIAM MASCORD, a subject of the King of Great Britain and Ireland, residing at St. Agness, 5 14 Castelnau, Barnes, London, S. W., England, have invented certain new and useful Improvements Relating to Apparatus for Feeding Web Reels or Rolls in Rotary Newspaper Printing and Similar Machines, (for 10 10 which I have filed application in Great Britain, May 16, 1919, Patent No. 152,705,) of which the following is a specification.

This invention relates to apparatus for feeding web reels or rolls in rotary newspaper printing and similar machines and relates to such machines as are provided with reel carriers adapted to carry a number of 15 reels and of being rotated or moved to bring the reels into position on the opposite side 20 of the apparatus in the manner described in the specification of the prior Patent No. 769659 of 1904.

According to the invention, I provide each 25 pair of the reel-carrying brackets for the reception of two reels and I support the corresponding driving band or bands upon the brackets in a position between the two reels so that the same driving band may be used 30 for feeding from one or other reel mounted upon and between the same brackets. The driving spindle receives movement through 35 bevel gear from a spindle extending along the side of the supporting frame and similarly receiving movement from a vertically disposed spindle also at the side of the frame and driven from a spindle radially disposed with respect to the axis of rotation of the frame. Means are provided such as described in the specification of the said prior 40 patent for reversing the movement of the driving bands according to the position of the reel to be fed with reference to the band.

The respective brackets adapted to carry 45 two reels are disposed one above the other in substantially the same manner as in the construction described in the specification of the said prior patent but the respective brackets are provided of greater strength and of greater length, means being provided for the 50 reception of the two reel spindles instead of the one. The driving spindle of each driving band is carried by and between the respective pairs of brackets in a position be-

neath and between the respective reels, and 55 pulleys advantageously of the kind described in the specification of the said prior patent and advantageously two in number are mounted upon the driving spindle. Corresponding pulleys are mounted upon a spindle carried by upwardly extending arms 60 whose lower ends are mounted on the driving spindle and a weighted lever or other means are provided to permit of the frame thus constituted being brought to one side or the other of a vertical line passing through 65 the driving spindle as may be desired according to the particular reel to be fed, the arrangement and operation being substantially the same as that described in the specification of the said prior patent. 70

On one side, however, a spindle extending along the frame is fitted with bevel gears by means of which movement may be imparted from a vertically disposed spindle mounted upon one side of the carrying frame and supported therefrom by means of brackets. Movement is imparted to the spindle last referred to from a spindle which extends centrally and transversely over the rotating base plate on which the frame is mounted 75 and movement is imparted to this spindle in substantially the same manner as described in the specification of the said prior patent. 80

It will be understood that brackets provided as described for the reception of two 85 reels may be disposed in vertical series on each side of the carrying frame so that thus the respective brackets on one side are level with those upon the other and thus four reels are disposed upon the same level, and movement may be imparted to the respective driving bands for each set of two reels in the manner described. 90

The application of the invention is illustrated, by way of example, in the accompanying 95 diagrammatic drawings in which Fig. 1 is a side elevation and Fig. 2 is an end elevation.

In carrying the invention into effect according to one particular construction, I 100 provide a rotatable base member *a* suitably supported on rollers or wheels *b* so as to turn about a central axis and upon such base member *a* there is provided a structure or carrying frame *c* carrying four pairs of 105 brackets *d* arranged in two groups of super-

posed pairs, each pair of brackets being adapted to carry two reels *e* of paper disposed in the same horizontal plane. At a point intermediate and below the bearings for the two reels on each bracket, there is provided a bearing for the reception of a spindle *f* which serves to carry two of the driving pulleys *g* and also at each extremity an arm *h* extending in the upward direction and carrying at a position intermediate and above the bearings for the axles of the reels *e* a second spindle *i* upon which is mounted a second pair of driving pulleys *g*, in positions adjusted with relation to 15 those of the lower spindle in such manner that two driving bands *j* may be carried between the two spindles *f* *i*. The lower spindle *f* also serves to carry at each extremity an upwardly directed weighted arm 20 *k* such that when the upper spindle *i* is thrown over from the vertical position in either direction, the weighted arms serve to maintain the spindle against return movement and thus to apply pressure of the driving bands upon the particular reel *e* of paper.

At one extremity each of the lower spindles *f* of the pairs of spindles is provided with a fixedly mounted bevel gear 30 wheel *l* and the bevel wheels of each of the spindles of the one tier are operated through a transverse shaft *m* arranged along the side of the structure and carrying bevel gear wheels *n* in suitable positions to gear with 35 those of the spindles. The transverse shafts *m* relating respectively to the upper and lower series of brackets *d* are preferably connected together by a vertically disposed shaft *o* carrying suitable bevel gears *p*. 40 Motion is conveniently transmitted to the lower end of this vertical shaft and also to the lower transverse spindle *m* by means of a spindle *q* at right angles thereto extend-

ing to the axis of rotation of the base member *a* and receiving motion through bevel gear *r* from a vertically disposed shaft *s* disposed in the axial position which in turn receives motion from a suitable driving shaft arranged below the apparatus.

I claim:

1. In a web reel carrier for printing machines, of the kind comprising a frame rotatable about a vertical axis and carrying pairs of brackets thereon for the support of the web reel spindles and carrying endless driving bands by means of which the web reels are rotated from gear deriving movement from a centrally disposed vertical shaft, the combination of pairs of brackets carried by the said frame, which brackets are adapted for the reception of two web reels and separate driving bands for each pair of brackets, the said driving bands being so mounted as to drive one or other of the web reels mounted on the respective brackets, substantially as described.

2. In a web reel carrier for printing machines, of the kind comprising a frame rotatable about a vertical axis and carrying pairs of brackets thereon for the support of the web reel spindles and carrying endless driving bands by means of which the web reels are rotated from gear deriving movement from a centrally disposed vertical shaft, the combination of pairs of brackets carried by the said frame, which brackets are adapted for the reception of two web reels and separate driving bands for each pair of brackets, the said driving bands being so mounted as to drive one or other of the web reels mounted on the respective brackets, and means for causing the movement of the said driving bands from the central vertically disposed driving spindle, substantially as described.

GEORGE WILLIAM MASCORD.
